DISPLAY SPINNER

Shirley McLarty, 417 Blanning St.,
Dallas, Tex. 75218

Filed Oct. 21, 1965, Ser. No. 87,688

Term of patent 14 years

(Cl. D1—2)

FIG. 1

FIG. 2

FIG. 3

FIG. 1 is a perspective view of a display spinner showing my new design;

FIG. 2 is a top plan view thereof; and

FIG. 3 is a front elevational view thereof, the rear being the same as the front shown.

I claim:

The ornamental design for a display spinner, as shown and described.
